GOLF GAME TARGET

Otto G. Arndt and James J. Arndt, both of 1708
S. Dahlia St., Denver, Colo. 80222

Filed Sept. 6, 1974, Ser. No. 503,971

Term of patent 14 years

Int. Cl. D21—01

U.S. Cl. D34—5 NN

Fig. 1

Fig. 2

Fig. 3

Fig. 4

Fig. 5

Fig. 6

FIG. 1 is a perspective view of a golf game target showing our new design;

FIG. 2 is a side elevational view of the design;

FIG. 3 is a transverse sectional view as taken from the indicated line 3—3 at FIG. 1;

FIG. 4 is a fragmentary detail sectional view as taken from the indicated line 4—4 at FIG. 3, but on an enlarged scale;

FIG. 5 is a top plan view of the design shown at FIG. 1, but on a reduced scale; and

FIG. 6 is a bottom view of the design on a reduced scale.

We claim:

The ornamental design for a golf game target, as shown.
